UNITED STATES PATENT OFFICE

118,478

DESIGN FOR A CURTAIN HOOK

Arthur M. Herschensohn, New York, N. Y.

Application November 16, 1939, Serial No. 88,314

Term of patent 3½ years

To all whom it may concern:

Be it known that I, Arthur M. Herschensohn, a citizen of the United States, residing in New York, county and State of New York, have invented a new, original, and ornamental Design for a Curtain Hook, of which the following is a specification, reference being had to the accompanying drawing, forming part thereof.

I claim:

The ornamental design for a curtain hook, as shown.

ARTHUR M. HERSCHENSOHN.
